UNITED STATES PATENT OFFICE.

WILLIAM H. CALKINS, OF COLUMBUS, OHIO.

STOVE.

SPECIFICATION forming part of Letters Patent No. 766,217, dated August 2, 1904.

Application filed December 7, 1903. Serial No. 184,100. (No model.)

To all whom it may concern:

Be it known that I, WILLIAM H. CALKINS, a citizen of the United States, residing at Columbus, in the county of Franklin and State 5 of Ohio, have invented a certain new and useful Improvement in Stoves, of which the following is a specification.

My invention relates to the improvement of heating-stoves, and has particular relation 10 to that class of stoves known as "gas-stoves."

The objects of my invention are to provide an improved construction of stove of this class wherein are combined improved means 15 for generating and radiating heat from a suitable burner, to so construct my improved stove as to insure the utilization of a comparatively large per cent. of the heat generated at the burner, and to produce other improvements the details of construction of 20 which will be more fully pointed out hereininafter. These objects I accomplish in the manner illustrated in the accompanying drawings, in which—

Figure 1 is a view in elevation of my improved stove. Fig. 2 is a plan view. Fig. 3 is a vertical section taken on varying planes as indicated by the dotted line $x-x$ of Fig. 2, and Fig. 4 is a transverse section on line $y-y$ of Fig. 1.

Similar numerals refer to similar parts throughout the several views.

In carrying out my invention I employ an upright main casing or drum portion 1, within the lower portion of which is adapted to 35 be supported a suitable gas-burner 2, the burner shown being in the nature of a ring-burner having upper side perforations and being supplied with gas through the medium of a gas-pipe 3. The form of the burner, 40 however, is immaterial, and, as is obvious, fuel other than gas may be used in the lower portion of the stove. The pipe 3 may be provided with a suitable form of air and gas mixer, (not herein shown,) and air is further 45 supplied to the interior of the casing 1 through the central opening 4 in the lower end of the casing. Within the casing 1 and arranged about the central portion thereof are a plurality of vertical pipes 5, these pipes connect- 50 ing opposing openings 5^a in the upper and

lower sides of said casing and being arranged, as shown, on the outer side of the burner 2. Rising from the central portion and upper side of the casing in a smaller supplemental casing 6 and into the upper portion of the 55 casing 6 lead the upper inturned end portions of vertical pipes 7, which extend downward on the outer side of said casing 6 and communicate with openings in the upper side of the casing 1, the connections of said last-men- 60 tioned casing and the lower ends of the pipes 7 being preferably effected between the openings 5^a. Leading downward through the otherwise closed upper end of the casing 6 is a central vertically-arranged pipe 8, the upper 65 end of the latter projecting above the casing-top 6, from which it is suspended, and the lower open end of said pipe 8 terminating, as shown in Fig. 3 of the drawings, a short distance above the top of the casing 1. With 70 the upper end of the pipe 8 is adapted to be connected a suitable smoke or discharge pipe. (Not herein shown.) In its lower portion the casing 1 is provided with a doorway which is adapted to be closed by a suitable hinged door 75 9, and said casing 1 is provided with suitable supporting-legs 10.

In operation it will be understood that the combined heat and products of combustion which rise from the flame at the burner 2 or 80 from other fuel used in the base portion of the stove-casing will pass through said casing 1 and pipes 7 into the upper portion of the casing 6 and thence downward, as indicated by the black arrows, to the lower end of the cas- 85 ing 6 and upward and outward through the pipe 8. This circulation of the heat and products of combustion within the casings and pipes 7 results in not only heating the surfaces of both the upper and lower casings and said 90 pipes 7, and thereby heating a comparatively large radiating-surface, but will also result, through the circulation about the pipes 5, in heating the latter and in causing a comparatively rapid passage of air through said pipes 95 5, which is discharged into the room wherein the stove is located in a heated condition.

From the construction and operation de- 100 scribed it will be understood that a comparatively simple stove construction is provided,

in which a large per cent. of the heat generated at the burner is utilized and in which a comparatively large radiating-surface is provided. Although described as a stove, it is 5 obvious that the construction set forth will be applicable to house-heating furnaces.

Having now fully described my invention, what I claim, and desire to secure by Letters Patent, is—

- 10 In a stove, the combination with a main casing 1 having a doorway and a plurality of pipes arranged about the center of said casing

and leading vertically therethrough, of a supplemental casing 6 mounted on said casing 1, a plurality of pipes 7 connecting the upper 15 portion of said casing 6 with the upper end of the casing 1 and a pipe 8 leading through and depending from the upper end of the casing 6, said pipe terminating at a point above the top of the casing 1.

WILLIAM H. CALKINS.

In presence of—
C. C. SHEPHERD,
A. L. PHELPS.
